Fig. 11.

UNITED STATES PATENT OFFICE.

OSCAR SINGER, OF CHICAGO, ILLINOIS, ASSIGNOR TO SINGER BROS. COMPANY, OF CHICAGO, ILLINOIS, A COPARTNERSHIP.

TRAVELING BAG.

Application filed January 29, 1923. Serial No. 615,588.

To all whom it may concern:

Be it known that I, OSCAR SINGER, a citizen of the United States, residing at Chicago, in the county of Cook and State 5 of Illinois, have invented certain new and useful Improvements in Traveling Bags, of which the following is a specification.

This invention relates in general to improvements in traveling bags but more 10 specifically to an improved re-enforcing or bracing means particularly adapted though not necessarily limited in its use with the type of bag commonly known as Gladstone bags.

15 Heretofore in bags of this character when the same is being transported by the handle, all of the strain or weight of the contents of the bag is exerted upon the lock or fastening means which is located upon the 20 top bar of the frame and to which frame bar the handle is also connected, with the result that eventually the lock will become injured and the frame bar becomes distorted or sprung out of shape especially 25 if heavy loads are frequently carried in the bag.

To overcome these difficulties and objections and to provide improved re-enforcing or bracing means for the fastening carrying 30 bar of the frame, thereby relieving the lock and fastening means from strain, is one of the objects of the present invention.

A further object is to provide an improved 35 device or means of this character which will also serve as a means to prevent the frame from collapsing or becoming crushed when weight or pressure is applied exterior of the bag.

A further object is to provide improved 40 re-enforcing or bracing means of this character which may be readily disconnected or adjusted when desired so that the same may be moved into a position out of the way so as not to interfere with the removal 45 of articles from the bag or the placing of articles thereinto.

A further object is to provide improved 45 re-enforcing or bracing means of this character which will be of a simple, durable, 50 cheap and light construction, adapted to be compactly arranged when not in use and which may be readily applied to any bag of this character or type.

To the attainment of these ends and the

accomplishment of other new and useful 55 objects as will appear, the invention consists in the features of novelty in substantially the construction, combination and arrangement of the several parts hereinafter more fully described and claimed and shown 60 in the accompanying drawings illustrating this invention and in which

Figure 1 is a top plan view of a traveling bag showing the same open, and having a 65 re-enforcing means constructed in accordance with the principles of this invention applied thereto.

Figure 2 is a longitudinal sectional view taken on line 2—2, Figure 1.

Figure 3 is an enlarged detail sectional 70 view taken on line 3—3, Figure 1.

Figure 4 is an enlarged detail sectional view taken on line 4—4, Figure 1.

Figure 5 is a top plan view of a portion of 75 one side of the bag showing a modified form of the invention.

Figure 6 is a detail sectional view taken on line 6—6, Figure 5.

Figure 7 is a view similar to Figure 1 of 80 still another form of the invention.

Figure 8 is a view partly in elevation and partly in section, showing the bag partly closed and as taken along the line 8—8, Figure 7, and with parts omitted.

Figure 9 is an enlarged detail sectional 85 view taken on line 9—9, Figure 7.

Figure 10 is an enlarged detail sectional view as taken on line 10—10, Figure 7.

Figure 11 is a view similar to Figure 1 of 90 another form of the invention.

Figure 12 is a sectional view on line 12—12, Figure 11.

Figure 13 is a detail perspective view of the brace bar.

Referring more particularly to the drawing and as usual in bags of this type, there are provided two frames which are connected together along one edge for pivotal movement, one with respect to the other. 95 one of the frames embodying a fastening device carrying member 10, to which the usual handle 11 is secured and side members 12, which are pivotally connected by means of suitable hinges 13, with the side members 14 of the frame member 15. To 100 the frame member 10 is connected the usual lock 16 and if desired suitable and the usual fastening devices 17 may also be connected 105

with the member 10. Co-operating with the lock 16 are the usual eyes or staple members 18, and co-operating members 19 are provided for the fastening devices 17.

5 A connecting bar 20 extends across the frame members intermediate the hinges 13 and forms the base or support for the contents of the bag as is usual in devices of this character.

10 When the bag is filled and closed and the same is transported by the handle 11, all strain from the weight of the contents of the bag is exerted upon the lock 16 and the fastening devices 17, if the latter are employed, with the result that eventually the lock will become injured and the frame member 10 will become distorted or sprung out of shape.

Similarly when the bag is closed and 20 weight or pressure is exerted upon the frame 10 from the outside of the bag the strain is exerted upon the lock or fastening device and the frame member 10 will also be distorted or sprung out of shape.

25 In order to overcome these objections suitable re-enforcing or bracing means are employed and in the form shown in Figures 1 to 4, the bracing means embodies a pair of bars or braces 21, which may be constructed of any suitable material but preferably of metal or some rigid yet slightly flexible material. One end of each of these bars or braces 21 is connected in any suitable manner preferably by means of an eye 30 22 (see particularly Figure 3) with each of the side members 12 of the frame by passing through a suitable opening 23 in the respective members 12. The other end of the braces or bars 21 are detachably anchored in any suitable manner with the frame member 10, adjacent the lock 16 and on each side thereof.

As a suitable means for fastening the free ends of the bars or braces 21 there 45 may be provided a stud 24 of any suitable construction but preferably of a slightly yielding nature and the extremity of each of the bars or braces 21 is provided with an aperture 25 therethrough adapted to receive the stud 24 by passing the apertured end of the bar or brace over the stud.

50 It will thus be manifest that with these bars or braces 21 secured in the position as shown in Figure 1, and when the bag is closed and lifted by the handle 11, the bars or braces 21 will prevent the weight within the bag from exerting its entire strain upon the lock, as the braces will distribute the strain to the member 10 and 55 away from the lock. When the bag is resting upon its edge and other articles are piled upon the bag or pressure is exerted upon the member 10 of the frame the braces 21 will also serve to prevent the member 10 60 from being sprung or distorted.

When it is desired, one end of each of the bars or braces may be detached by disengaging the extremity from the stud 24, after which the bars or braces may be folded with respect to and into the bag into the position shown in dotted lines in Figure 1.

65 Arranged within the bag is a partition or flap 26, which is connected along one edge preferably to the bar 20. This partition or flap is provided with supplemental flaps 27, to receive articles thereunder and is adapted to be positioned to rest upon either of the frames of the bag when the bag is open. When the bag is closed, the flap 26 engages and rests against the bars or braces 21, which latter, extending across the frame, serve as a means for supporting the flap 26 and thereby preventing the flap from being crushed. Should the articles under the flap 27 cause the same to bulge, the bars or braces 21 will not interfere therewith but the bulging portion will project between the bars or braces 21.

70 In the form of the invention shown in Figure 5, there is provided a single bar or brace which preferably consists of sections 28-29 pivotally connected as at 30. The free end of the section 28 is pivotally anchored as at 31 with the frame member 10 and the free extremity of the section 29 is provided with an aperture 32 over which, if desired, a cap 33 may be arranged.

75 Secured to the bar 20 is an ear or projection 34 which has mounted thereupon a suitable stud 35, preferably of a yielding nature and which stud 35 is adapted to pass into the opening 32 in the end of the section 29 of the brace to receive the cap 33, thereby detachably anchoring the free end of the section 29.

80 In this form of the invention the member 10 of the frame which carries the fastening device 16 is braced directly from a point diametrically opposite to the pivot 31 and preferably from the bar 20.

85 When the flap 26, in this form of the invention, is folded over the frame section containing the brace, the brace or re-enforcing bar will serve as an additional support for the flap 26.

90 When not in use or when it is desired to detach the brace, the free extremity of the section 29 of the brace is detached from the stud 35, after which the sections 28 and 29 may be folded as indicated in dotted lines in Figure 5, and moved to a position that they will pass beneath the adjacent portion of the frame member 10.

95 Obviously this form of brace will also serve as a means for preventing the frame member 10 from being distorted when the bag is closed and pressure is exerted from the outside of the bag.

In the form of the invention shown in Figures 7 to 10, the bars or braces 36 are pivotally connected by one extremity as at 37, in any desired or suitable manner such as by means of an eye which passes loosely through an ear or clip 38, and which latter is secured to the bar 39 which extends across the base or the back between the two hinged sections 40—41 and intermediate the hinges 18. This bar 39 re-enforces or braces the bottom and serves as a means for supporting the weight of the contents of the bag.

The ears or clips 38 may be secured at any desired point throughout the length of the bar 39 and are fastened thereto in any suitable manner.

The free end of each of the braces 36 is adapted to be detachably connected with the frame member 10 of the section 40 and any suitable fastening means may be provided for that purpose. To that end there may be provided a stud 42 which is adapted to enter an aperture 43 in the end of the bar or brace 36 and yield slightly so that the end of the bar or brace may be snapped thereover and as readily disengaged from the stud.

With this improved construction it will be manifest that the bar 39 will be braced and re-enforced by the bars or braces 36 to prevent the bar 39 from sagging or becoming distorted when the strain of the weight of the contents of the bag is exerted thereupon when the bag is lifted by the handle 11. Similarly, the member 42 of the frame 10 will also be re-enforced or braced by the bars or braces 36 when the bag is lifted by the handle.

These braces or bars 36 also serve as a means for preventing distortion or springing of the bar 39 and the frame member 10 when pressure is exerted upon the bag from the exterior thereof.

When not in use the free extremities of the bars or braces 36 may be detached from the respective studs 42 and folded into the bag in the position shown in dotted lines in Figure 7.

In the form of the invention shown in Figures 11 to 18, the brace bar 44 is of a length slightly greater than the width of the partition or flap 45.

As shown in Figure 11, two of these braces are employed and the flap or partition 45 is secured thereto in any suitable manner beneath the material or covering for the partition so as not to interfere with the flaps or pockets 46—47, which are preferably disposed on opposite sides of the partition. Each of these braces 44 is connected with the bar 39 preferably by means of a hinge 48, one portion 49 of the hinge being anchored to the bar 39.

The free extremity of the brace 44 is deflected laterally as at 50 and shaped to form

a downwardly opening hook shaped portion 51. This hook and the portion 50 of the brace is disposed beyond the free edge 52 of the flap 45 and is adapted to engage over the edge 53 of the frame member 10, and which edge 53 is arranged perpendicular to the body portion of the frame member 10.

The edge 53 of the member 10 is so disposed that when the frame members of the bag are closed the edge 54 of the frame member 15 will be overlapped by the edge 53 of the member 10, as shown in Figure 12, and the edge 54 will engage and rest upon the braces 44 adjacent the edge 52 of the flap or partition 45. This construction will permit the frame members 15 and 10 to be held in proper position with respect to each other and against lateral springing movement inwardly when the frame members are closed.

The braces 44 serve as a means for supporting the flap or partition 45 and being disposed beneath the pockets 46 and 47 will not interfere with the placing of articles in the pockets and especially the pocket 47, and which articles may cause the pockets to bulge outwardly.

In this form of the invention it will be manifest that the portion 53 of the frame member 10 to which the handle 11 is secured will be re-enforced or braced directly from the bar 39 and will prevent the frame member 10 or any portion thereof from springing out of shape or becoming distorted under the stress of the weight within the bag. Furthermore the braces will re-enforce the frame member 10 as well as the bar 39 against being distorted when the strain or pressure is exerted upon the bag from the exterior thereof. Furthermore the braces 44 will not interfere with the turning of the flap or partition 45 from a position extending across one of the frame members to a position to extend across the other frame member when the bag is open as shown in Figure 11.

While the preferred forms of the invention have been herein shown and described, it is to be understood that various changes may be made in the details of construction and in the combination and arrangement of the several parts, within the scope of the claims, without departing from the spirit of this invention.

What is claimed as new is:

1. A bag of the character described embodying frames connected for pivotal movement one with relation to the other, a locking device carried by one of the members of one of the frames, and a re-enforcing bar or brace pivotally connected at one of its ends to one of the members of the frame, said bar or brace extending across the frame and connected at its other end to the lock

- carrying frame member for restraining the last said member against deflection, one of the ends of the said bar or brace being detachable with relation to its respective frame member.
2. A bag of the character described embodying co-operating frames connected together along one edge for hinged movement one with relation to the other, fastening means for the free edges of the frames, a member extending across the frames adjacent the hinged edges and stationary with respect to one of the frames, and a re-enforcing bar or brace extending across that frame which is movable with respect to the said member, means pivotally anchoring one end of the bar or brace, and means detachably anchoring the other end of the bar or brace.
3. A bag of the character described embodying frames connected together at one edge for hinged movement one with relation to the other, a stationary member extending across the frames adjacent their hinged edges and in a direction lengthwise of the pivot of the frames, a bar or brace extending across one of the frames from the said stationary member to that frame member which is opposite thereto, means pivotally connecting one end of the bar or brace with the said stationary member, and means detachably connecting the other end of the bar or brace with the last recited frame member.
4. A bag of the character described embodying co-operating frames connected together along one edge for hinged movement one with respect to the other, a member extending across the frames adjacent the hinged edges, a handle, connected with one of the frame members opposite to the first recited member, a re-enforcing brace hingedly connected with the first recited member, and means detachably connecting the free end of the brace with the said handle carrying frame member.
5. A bag of the character described embodying co-operating frames connected together along one edge for hinged movement one with respect to the other, a member extending across the frames adjacent the hinged edges, a handle connected with one of the frame members opposite to the first recited member, a re-enforcing brace hingedly connected with the first recited member, and a hook shaped portion at the free end of said brace adapted to detachably engage over the edge of the said handle carrying member.
6. A bag of the character described embodying co-operating frames connected together along one edge for hinged movement one with relation to the other, a member extending across the frames adjacent said edge, a flap flexibly secured along one edge ad-
- jaacent said member, a bracing member connected with the flap, means pivotally anchoring one end of said bracing member to the first recited member, the other end of the bracing member extending beyond the opposite edge of the flap, and means detachably anchoring the free end of said bracing member to a frame member opposite to the first recited member.
7. A bag of the character described embodying co-operating frames connected together along one edge for hinged movement one with relation to the other, a member extending across the frames adjacent said edge, a flap flexibly secured along one edge adjacent said member, a bracing member connected with the flap, means pivotally anchoring one end of said bracing member to the first recited member, the other end of the bracing member extending beyond the opposite edge of the flap, and means connected with the free end of said bracing member and adapted to detachably engage over one edge of the frame member opposite to the first recited member.
8. A bag of the character described embodying frame members connected together at one edge for hinged movement one with relation to the other, a bar or member extending across the frames adjacent the said hinged connection, a brace pivotally connected by one end to the said bar, means at the free end of the brace for detachably connecting said end with a frame member opposite the said bar, and a flap connected with the said brace and movable therewith, said flap serving as a closure for one of the bag sections, the free edge of the other frame member adapted to engage a portion of the brace when the frame members are closed with respect to each other.
9. A bag of the character described embodying frame members connected together at one edge for hinged movement one with relation to the other, a bar or member extending across the frames adjacent the said hinged connection, a brace pivotally connected by one end to the said bar, means at the free end of the brace for detachably connecting said end with a frame member opposite the said bar, and a flap connected with the said brace and movable therewith, said flap serving as a closure for one of the bag sections, the free edge of the other frame member adapted to engage and rest against a portion of the brace when the frame members are closed with respect to each other, a portion of one of the frame members being adapted to overlap a portion of the other frame and adjacent the detachably anchored end of the brace.
10. A bag of the character described embodying co-operating frames connected together along one edge for hinged movement one with relation to the other, a member ex-

tending across the frames adjacent said edge, a flap flexibly secured along one edge adjacent said member, a bracing member connected with the flap, means pivotally anchoring one end of said bracing member to the first recited member, and means detachably anchoring the free end of said

5 bracing member to a frame member opposite to the first recited member.

In testimony whereof I have signed my name to this specification on this 22 day of January, A. D. 1923.

OSCAR SINGER.
